UNITED STATES PATENT OFFICE.

MAXWELL B. KENDALL, OF CHICAGO, ILLINOIS.

CLOSET CLOTHES-HANGER.

1,361,070.

Specification of Letters Patent.

Patented Dec. 7, 1920.

Application filed January 30, 1920. Serial No. 355,085.

To all whom it may concern:

Be it known that I, MAXWELL B. KENDALL, a citizen of the United States, and a resident of the city of Chicago, in the county of Cook 5 and State of Illinois, have invented certain new and useful Improvements in Closet Clothes-Hangers; and I do hereby declare that the following is a full, clear, and exact description of the same, reference being had 10 to the accompanying drawings, and to the numerals of reference marked thereon, which form a part of this specification.

This invention relates to closet wardrobes and means for hanging clothes and other 15 articles therein.

In the ordinary closet it is frequently difficult to see exactly what clothes are hanging therein and further only the walls are utilized for hooks from which clothes are hung.

20 One of the objects of the present invention is to provide means for supporting clothes intermediate the rear wall and the opening of the closet.

A further object of the invention is to provide a closet clothes support which may be 25 swung out of the closet when it is desired to remove clothes therefrom, to hang clothes thereon or to reach the hooks on the rear wall of the closet.

30 Other and further important objects of this invention will be apparent from the disclosures in the drawings and specification.

The invention, (in a preferred form) is illustrated in the drawings and hereinafter 35 more fully described.

On the drawings:

Figure 1 is a horizontal section through the upper part of a closet with the present improvements applied thereto.

40 Fig. 2 is an elevation of the clothes support and its own supporting means.

Fig. 3 is a section on the line 3—3 of Fig. 2.

Fig. 4 is a section on the line 4—4 of Fig. 2.

Fig. 5 is a section on the line 5—5 of Fig. 2.

45 Fig. 6 is a plan view of the parts shown in Fig. 5.

Fig. 7 is a plan view of a portion of the supporting means for the clothes support when the latter is in extended position.

50 Fig. 8 is a section on the line 8—8 of Fig. 7.

Fig. 9 is a section on the line 9—9 of Fig. 1.

Fig. 10 is a section on the line 10—10 of Fig. 1.

As shown on the drawings:

55 A closet of rectangular form is shown having a rear wall 1, side walls 2 and inwardly

extending front walls 3 with an opening 4 therebetween adapted to be closed by a door, curtain or other means. Along the rear wall a series of coat hooks 5 may be arranged.

Within the closet a pivoted or folding clothes support is provided which in the form shown in the drawings comprises three pivoted sections 6, 7 and 8. The last of 65 these three sections forms the clothes support proper, the other two sections serving merely as an extensible and movable support therefor.

The section 6 may be formed of sheet 70 metal flanged at 9 along its upper and lower edges. These flanges are apertured at one end for the passage of a bolt 10 by which the section 6 is connected to a hinge 11 secured to the inner face of one of the front 75 walls 3 of the closet.

The section 7 is similarly formed with flanges 12 adapted to overlap the flanges 9 of the section 6 for pivotal attachment thereto by a bolt or pintle 13. Sleeves 14 and 15 80 are arranged on the bolts 10 and 13 between the flanges on the parts 11, 6 and 7 to prevent the flanges becoming distorted or bent out of shape. Both members 6 and 7 may to advantage be corrugated as shown to give 85 greater stiffness and reduce the twisting effect due to the weight of the clothes suspended from the support 8.

The flanges 9 and 12 and those on the hinge 11 are also arranged mutually to support each other when the members are moved into the position shown in Fig. 7. In that position the flanges on the hinge 11 and the flanges 12 butt against each other, while the flanges 9 extend along the inner side of each 90 adjacent pair of flanges 12 and those on the hinge 11 thereby preventing relative vertical movement of the flanges 12 with respect to the flanges on the hinge 11.

The clothes support proper 8 may conveniently be formed from a round rod bent at right angles to provide a vertical portion 14, which passes through apertures in the outer ends of the flanges 12, and a horizontal portion 15. A corrugated rod 16 or a bar 105 notched along its upper edge extends from the end of the horizontal portion 15 to the bottom of the vertical part 14. The corrugations or notches in the bar 16 enable hangers to be attached thereto at any desired 110 points therealong. If the support 8 is of unusual length or designed for use with

heavy overcoats or the like, a cross-brace 5 may be provided between the bar 16 and the portion 15.

Around the part 14 are arranged two sleeves 17 and 18, the first being arranged between the flanges 12, while the other is below the lower flange 12. These sleeves not only support the flanges and part 14, but also provide means for releasably holding the clothes support 8 in desired angular position with respect to the member 7. For this purpose a spring 19 is mounted on the lower end of the part 14 and held in position by a nut 20 on the lower end of the 15 latter. This spring bears at its upper end on the sleeve 18 through the intermediary of an eye 21 at the end of the corrugated rod 16 so that the part 14 is normally drawn downward. On the upper end of the part 20 14 a pin or other projection 22 is provided adapted to releasably engage one or other of a series of notches or grooves 23 in the flange 12 under the action of the spring 19. A jerk or strong pull on the clothes support 25 8 will suffice, however, to raise the part 14 sufficiently to enable the pin to clear the grooves 23 and thereby allow the clothes support to turn relatively to the member 7. Grooves 23 are provided in both flanges 12 30 to allow the member 7 to be reversed in position.

Means may also advantageously be provided for yieldingly holding the members 6 and 7 in position within the closet. As 35 shown, these means include a spring latch 24 (Fig. 10) adapted to engage the upper flange 12 of the member 7 and releasably hold the latter parallel to the side wall 2.

There is considerable tendency for the device 40 to sag under heavy loads and such sagging not only tends to distort the device but also to move the member 7 out of engagement with the latch 24. Accordingly an inclined support 26 is preferably provided for the end of the member 7 when the latter lies adjacent the closet wall. Conveniently the latch 24 and the support 26 are formed from a single plate by slitting the latter along parallel lines from both its 45 upper and lower edges and bending the intervening tongues of metal outward, the upper tongue forming the latch 24 while the lower tongue forms the support 26. The intervening portion of the plate 27 serves to 50 prevent the end of the member 7 striking against and marring the wall of the closet. The latch 24 is arranged near the end of the member 7 so that as the clothes support 8 swings forwardly (as indicated in the first 55 dotted line position of Fig. 1) the rod 15 strikes the inclined end of the latch and lifts it upwardly to release the member 7. The parts may then be brought into the second dotted line position shown in Fig. 1. 60 The engaging shoulder of the latch 24 is

preferably inclined downwardly and outwardly as shown so that the member 7 may be released by a quick pull on the clothes support 8.

Another latch 25 is provided for holding 70 the member 6 parallel to the wall 3. In this case the latch is released by engagement of the member 7 with its inclined end. The latch 25 is preferably formed with a vertical engaging shoulder so that it cannot be 75 released by a quick pull of the support but only by the engagement of the member 7 with its inclined end.

I am aware that numerous details of construction may be varied through a wide 80 range without departing from the principles of this invention, and I therefore do not purpose limiting the patent granted otherwise than necessitated by the prior art.

I claim as my invention:

1. A closet having inwardly projecting walls at each side, a bar pivotally connected to one of said walls adjacent its inner margin, and adapted to extend toward the adjacent side wall, a second bar pivotally connected at one end to the free end of the first bar and adapted to extend rearwardly along the side wall and a clothes support pivotally connected to the other end of the second bar. 95

2. A closet having in combination therewith a bar pivotally connected at one end to the wall of the closet, a vertical hinge portion at the other end of the bar, a clothes support having a downwardly projecting 100 portion extending through said hinge portion, a pin at the upper end of said downwardly projecting portion adapted to engage releasably a groove in the top of said hinge portion, and a spring adapted to hold 105 said pin in yielding engagement with said groove.

3. A closet having in combination therewith a bar pivotally connected at one end to the wall of the closet, a vertical hinge portion at the other end of the bar, a clothes support of right-angle triangular form having a vertical member extending through said hinge portion, a horizontal member and a corrugated hypotenuse member connecting the outer end of the horizontal member to the lower end of the vertical member, a pin at the upper end of the vertical member adapted to engage releasably a groove in the top of said hinge portion, and a 110 spring adapted to hold said pin in yielding engagement with said groove. 115

4. A closet having inwardly projecting walls at each side, a bar pivotally connected to one of said walls adjacent its inner margin and adapted normally to extend toward the adjacent side wall, a second bar pivotally connected at one end to the free end of the first bar and adapted normally to extend rearwardly along the side wall, a 12 12

13

- clothes support pivotally connected to the other end of the second bar, and yielding means for releasably holding the first and second bars in their normal positions.
- 5 5. A closet having in combination therewith a horizontally flanged hinge, a member having flanges overlapping the flanges of the hinge member, and pivotally connected thereto, a second member having
- 10 flanges overlapping and pivotally connected to the flanges of the first member, the flanges of the hinge and second member being in substantially the same plane, and a clothes support pivotally connected to the
- 15 flanges of the second member.
6. A closet having in combination therewith a horizontally flanged hinge, a member having flanges overlapping the flanges of the hinge and pivotally connected thereto,
- 20 a clothes support and a pivotal connection between said member and the support.
7. A closet having in combination therewith a member pivotally connected at one end to a wall of the closet and normally extending along a wall of the closet, a clothes support pivotally connected to the other
- 25

end of the member, and a bracket secured to the wall of the closet adjacent the last mentioned end of the member having a latch adapted to engage the upper margin 30 of the member for releasably holding it in its normal position and a projection adapted to engage the lower margin of the member for holding the latter in engagement with the latch.

35

8. A closet having in combination therewith a member pivotally connected at one end to a wall of the closet and normally extending along a wall of the closet, a clothes support pivotally connected to the 40 other end of said member, and means for preventing contact of the last mentioned end of the member with the wall of the closet.

In testimony whereof I have hereunto 45 subscribed my name in the presence of two subscribing witnesses.

MAXWELL B. KENDALL.
